UNITED STATES PATENT OFFICE.

WILL H. VAN GUILDER, OF NEW ROCHELLE, NEW YORK.

MOLDING-MACHINE.

1,215,436.

Specification of Letters Patent. Patented Feb. 13, 1917.

Application filed April 25, 1914. Serial No. 834,339.

To all whom it may concern:

Be it known that I, WILL H. VAN GUILDER, of New Rochelle, county of Westchester, and State of New York, have invented a 5 new and useful Improvement in Molding-Machines, which improvement is fully set forth in the following specification and shown in the accompanying drawings.

The present invention relates to molding 10 machines and more particularly to that type designed for forming cement walls *in situ*, an object of the invention being to provide an attachment for that type of molding machine disclosed in the application of Willis 15 N. Britton filed July 13th, 1910, Ser. #570,585, such attachment being designed for forming pilasters upon the walls. A further object of the invention is to provide a pilaster attachment which may be readily 20 adjusted to form pilasters of different sizes. To these and other ends, the invention consists in certain parts and combinations of parts all of which will be hereinafter described, the novel features being pointed out 25 in the appended claims.

In the drawings:

Figure 1 is a top view of the attachment showing the latter constructed for forming a corner pilaster and connecting two molding 30 machines of the type set forth in the aforesaid Britton application;

Fig. 2 is a view of one of the end walls of the corner pilaster;

Fig. 3 is a section on the line *a—a*, Fig. 2;

Fig. 4 is a section on the line *b—b*, Fig. 2;

Fig. 5 is a perspective view of a portion of the frame of the corner pilaster;

Fig. 6 is a top view of another pilaster attachment constructed in accordance with 40 this invention, this attachment being designed for forming a pilaster on a straight wall to permit the introduction of flues within the wall, and being shown as one of the connections between two molding machines of the type shown in the aforesaid Britton application;

Fig. 7 is a perspective view of the pilaster attachment shown in Fig. 6; and

Fig. 8 is a detail view of one of the ends 50 of one of the walls of the machine shown in the aforesaid Britton application.

In the Britton application aforesaid, the molding machine embodies two outer face-forming members or walls 1 and 2 connected together at their ends by connecting 55 means 3 which also support two inner face-

forming members or walls 4 and 5 for forming an air chamber, the walls 1, 2, 4 and 5 being movable relatively to each other for the purpose of removing the machine after 60 the molding operation has been completed.

The pilaster attachment, shown in Figs. 1 to 5 inclusive, is capable of forming a corner pilaster when supported by two of the aforesaid Britton machines or any other 65 suitable means and it preferably embodies four walls, two front face-forming members and two lateral face-forming members, the front face-forming members being arranged at angles to each other and preferably piv- 70 otted at their meeting edges while the lateral face-forming members are arranged at the other edges of the front face-forming members and extend laterally with relation to said members, being preferably rigid there- 75 with, but adjustably connected thereto so that the projection of the pilaster from the main wall may be varied. Preferably, also the length of the front face-forming members may be varied for the purpose of vary- 80 ing the width of the pilaster.

The two front face-forming members may each embody a vertical frame piece 6 having lugs 7 extended therefrom and connected by a pintle 8 with the lugs 7 of the other 85 front face-forming member. From the ends of the upright frame piece 6, two laterally-extending frame pieces 9 are provided, each having an angle bar 10 secured to the outer face thereof and extending parallel therewith, the outer ends of the angle bars preferably being connected by a brace member 11 so that the parts 6, 9, 10 and 11 form a frame section. A sheet metal plate 12 with laterally-turned upper and lower edges is 90 secured to the frame pieces 9 and extends parallel to the frame section in spaced relation to the angle bars 10.

Between the angle bars 10 and the sheet metal plate 12, another frame section forming part of the front face-forming member is adjustable and preferably comprises two parallel bars 13 having a sheet metal plate 14 with laterally-turned edges secured thereto, bolts 15 being passed through openings 100 16 in the angle bars 10 in order to engage the bars 13 for holding the two frame sections in different adjusted positions with relation to each other for the purpose of increasing or decreasing the width of the face 110 of the pilaster.

In this embodiment, a lateral face-form-

ing member is preferably adjustable transversely of the plane of each of the front face-forming members and to this end preferably comprises an upright member 17 having lateral extensions 18 at its opposite ends to one face of which angle bars 19 are bolted at 20, these angle bars being adjustably connected to the front face-forming member preferably by forming the bars 13 with laterally-deflected ends 21 which by bolts 22 are secured to the angle bars 19, the latter being provided with a number of openings 23 to permit the adjustment. The angle bars 19, by being secured to one face 15 of the extensions 18 permit the laterally deflected ends 21 to lie in a plane with the lateral extension 18 in order that the sheet metal plate 24 having laterally-turned upper and lower edges 25 and secured to the frame 20 of the lateral face-forming member may overlap a lateral extension 26 on the plate 14 so that no space will be provided when the lateral face-forming member is adjusted on the front face-forming member.

25 The aforesaid Britton molding machine has its outer face-forming members 1 and 2 provided with eyes 27 at the opposite ends thereof and in order to support the corner pilaster from two of these machines, one of the lateral face-forming members is provided with alined pintles 28 which are adapted to be passed through the eyes 27 on one end of said Britton molding machine. The other lateral face-forming member is 30 provided with two alined projections 29 carried by a bolt or slide 30 arranged for vertical movement on the upright frame piece 17, thus providing a locking device for engagement within eyes 27 at one end of an 35 other Britton molding machine.

40 For forming a molding chamber between the Britton molding machines there may also be combined with the corner pilaster, an angular wall 31 which does not *per se* form the subject matter of the present invention, but which is detachably connected to the molding machines in a manner similar to the corner pilaster. An angular core piece 45 32 may be supported at its ends on the molding machines in any suitable manner, this feature not forming the subject matter of the present invention.

45 In the use of the invention, the two molding machines are arranged at angles to each other and are connected together by the angular wall 31 and the corner pilaster, the core piece 32 being placed in position to form the air chamber between the molding machines. After the molding chamber between the machine has been filled, the corner pilaster is detached by raising the locking member 30 to disengage the projections 29 from the eyes 27 after which the front face-forming member carrying the lateral face-forming member which is provided with

the locking member is swung outwardly on the hinges 7 and 8, when the other outer face-forming members and the lateral face-forming member carried thereby are swung on the pintles 28 as a pivot, thus permitting 70 the pilaster to be removed without injury to the molded wall.

The pilaster attachment shown in Figs. 6 and 7 is designed for forming pilasters on a straight wall either for ornamentation, 75 for strength or to permit flues to be mounted within a wall as shown in Fig. 6. This pilaster embodies a front face-forming member having a lateral face-forming member rigidly but adjustably secured to one end thereof, the parts being the same as one of front face-forming members and one of the lateral face-forming members of the attachment shown in Figs. 1 to 5. This pilaster also embodies a second lateral face-forming member 80 which is pivotally connected to the single front face-forming member. This second lateral face-forming member embodies an upright frame piece 33 having integral lugs 34 connected by pivot bolts 35 85 to the integral lugs 7 on the frame piece 6. Adjustably arranged on the frame piece 33 is a frame section of U-shape having an upright piece 36 formed with lateral extensions 37 at its opposite ends to which are 90 bolted bars 38 which are preferably provided with a series of openings 39 for the reception of bolts 40, the latter connecting the bars 38 with the upright frame piece 33. The upright frame piece 36 carries a locking member 30 which is provided with alined projections 29 for engagement within 95 the eyes 27 on one of the aforesaid Britton molding machines.

100 The embodiment of the invention illustrated in detail in Fig. 6 is adapted for forming a pilaster on an otherwise flat wall and when so used may connect two molding machines of the type described in the aforesaid Britton application and illustrated partially at *x* and *y* in Fig. 6 of the drawings of this application, the pilaster attachment being illustrated by the connecting part shown at *z*. Combined with said attachment is a connecting member *w* which is not claimed 105 *per se* in this application but forms the subject matter of another application filed by Willis N. Britton on March 15th, 1913, Serial #752,130. With this combination of parts, a wall may be molded about vertical flues *t*. After the wall is molded, the attachments *w* and *z* are disconnected from the molding machines *x* and *y*, permitting the latter also to be removed.

110 In both embodiments of the invention, a pilaster attachment is provided for connecting two molding machines of a known type to adapt such machines for more extended use. This pilaster attachment may be readily connected to or detached from the ma- 115 120 125 130

chines and is extensible or adjustable to adapt it for forming pilasters of different depths and widths. The attachment is so constructed that it may be moved from the 5 formed or molded wall without injury to the corners of such wall.

What I claim as my invention and desire to secure by Letters Patent, is:

1. In combination with two molding apparatus each having two walls for forming a molding space between them, and a connection between the walls by which the latter may be moved toward and from each other, a pilaster attachment connecting a 10 wall on each apparatus and having a front face-forming wall and a lateral face-forming wall at an angle to the front face-forming wall, said lateral face-forming wall being hinged to one molding apparatus in 15 order to permit the attachment to swing away from the corner formed thereby and a latch for securing the swinging end of the pilaster attachment to the other apparatus.
2. In combination with two molding apparatus each having two connected walls for forming a molding space between them, and a connection between the walls by which the latter may be moved toward and from each other, a pilaster attachment connecting a 20 wall on each apparatus and having a front face-forming wall and a lateral face-forming wall, said lateral face-forming wall being hinged to the molding machine in order to 25 permit the attachment to swing on one molding apparatus in order to be carried away from the corner formed by such attachment, and a latch for securing the swinging end of the pilaster attachment on the other apparatus.

3. In combination with two molding apparatus each having two connected walls for forming a molding space between them and a connection between the walls by which the latter may be moved toward and from each other, a pilaster attachment connecting a 40 wall on each apparatus and having a longitudinally adjustable front face-forming member and a lateral face-forming member rigid with and adjustable on the front face-forming member, said lateral face-forming member being hinged to one molding machine in order to permit the attachment to swing away from the corner formed by such attachment and a latch for securing the swinging end of the pilaster attachment on the apparatus.

4. A pilaster mold comprising two front face-forming members hinged together and, 55 when in molding position, arranged at angles to each other, and two side face-forming members each rigidly secured to a front face-forming member at an angle to the latter, the ends of said side face-forming walls when in operative position being

spaced apart and having at their free edges means adapting said members for attachment to two molding machines at angles to each other.

5. A pilaster mold comprising two connected front face-forming members arranged at right angles to each other, and two side face-forming members connected to the front face-forming members and arranged at right angles to each other, and to the front face-forming members, the side face-forming members being shorter than the front face-forming members so that their ends are spaced apart, and the free edges of said side face-forming members 75 having means adapting the mold for attachment to two molding machines.

6. A pilaster mold comprising two adjustable face-forming members hinged together at their meeting edges and adapted 80 to lie at right angles to each other, two adjustable side face-forming members rigidly secured to the edges of the front face-forming members at right angles to said member, the ends of said side face forming walls when in operative position being 85 spaced apart and having at their free edges means adapting said members for attachment to two molding machines at angles to each other.

7. A pilaster mold comprising two side face-forming members each provided with extensions, a front face-forming member 90 adjustably connected to said extensions, the side face-forming members each having at 100 their free edges alined projections adapting the mold for attachment to two molding machines.

8. A pilaster mold comprising two side face-forming members, a front face-forming member connecting the side face-forming members, the side face-forming members having means at their free ends adapting them for attachment to two molding machines, and a rear wall coextensive with the 105 distance between the two side face-forming members and having means at its free edges adapting it for attachment to two molding machines to which the side walls are connected.

9. A pilaster mold comprising two connected front face-forming members arranged at right angles to each other, two side face-forming members connected to 110 and arranged at right angles to each other and to the front face-forming members, the side face-forming members being shorter than the front face-forming members so that their ends are spaced apart, and the free edges of said side face-forming members 115 having means adapting the mold for attachment to two molding machines, and two angularly arranged rear walls parallel with the front face-forming member, projecting into the space between the end walls 120 125 130

and having means at their free edges for connecting them to two molding machines to which the side face-forming members are secured.

10. A mold comprising a frame embodying two parallel bars having laterally-turned ends, a wall secured to said frame, a U-shaped frame having its arms adjustably secured to the laterally-turned ends, and a wall formed of two overlapping portions, one secured to the U-shaped frame, and the other to the first named frame at an angle to the plane of the latter.

11. A mold comprising a frame member having two parallel bars with laterally-turned ends formed with bolt openings, a

sheet metal wall secured to the inner face of said frame, two angle irons provided with bolt openings and adjustably secured to the laterally-turned ends, a vertical frame piece having laterally-extending ends also secured to the angle bars in a plane with the laterally-turned ends of the first-named frame, and a wall formed by two over-lapping sheet metal pieces, one secured 25 to the first-named frame piece and the other secured to the vertical frame piece.

WILL H. VAN GUILDER.
